UNITED STATES PATENT OFFICE.

THOMAS ELLIOTT, OF CINCINNATI, OHIO, ASSIGNOR TO THE CINCINNATI CAR COMPANY, OF WINTON PLACE, OHIO, A CORPORATION OF OHIO.

ELECTRICALLY-OPERATED RAILWAY-CAR DOOR.

Application filed December 1, 1924. Serial No. 753,405.

This invention relates to improvements in electrically operated railway car doors for use on city and interurban railway cars in particular.

5 The invention comprises, essentially, a door and a lever connected thereto and adapted by a swinging movement through substantially the arc of half a circle to open and close the door, and of an electric motor 10 and lever-actuating mechanism adapted to be given a rotary-reciprocating movement by the motor and to thereby actuate the lever in the arc of its movement, in first one direction and then the other.

15 My invention further consists in the arrangement and organization of this lever actuator, which is made up of two essential features, one a rotatable clutch member and the other an oscillatable head adapted to be 20 actuated through a clutch connection between it and the clutch member, combined with stops which act to limit the movements of the oscillatable head so that each time the head oscillates far enough to swing the door 25 operating lever from one position to the other, the head will come to rest and remain in that position until the electric motor is reversed, by any suitable switch, and the clutch member made to reverse its direction 30 of rotary travel and to carry the oscillatable head back to the other extreme of its movement; so that the door actuating lever will be swung by the oscillatable head from one extreme of its movement to the other, whereby the door is alternately opened and closed. 35

My invention further consists in numerous features in the nature of subcombinations and of detail.

In the accompanying drawings forming a 40 part of this specification in which like reference characters indicate corresponding parts:

Figure 1 is an elevation of a portion of a car body showing my improved door operating mechanism located therein.

45 Figure 2 is a transverse sectional view through one side wall and inner wall of the car body showing my mechanism in an elevation, such view being on the line 2-2 of Figure 1, looking in the direction of the arrow.

Figure 2^a is a detail view showing in vertical section the lower part of the dash pot and illustrating the air inlet and outlet ports and adjunct devices.

50 Figure 3 is a vertical transverse sectional

view of the lever actuator taken on the line 3-3 of Figure 4, looking in the direction of the arrow.

Figure 4 is a partial elevation and partial sectional view taken on the line 4-4 of Figure 3, looking in the direction of the arrow; in which view the oscillatable head is shown in the position of one limit of its movement, that which it occupies when the door is closed, and the door lever is in the position shown in dotted lines in Figure 1.

Figure 5 is a like view to that shown in Figure 4 except that the oscillatable head is shown in the other position of its extreme movement, in which case the door lever will 70 be in the position shown in full lines in Figure 1.

Figure 6 is a detail vertical sectional view of the hub member of the oscillatable head with the door lever shown therein and 75 broken off at one end.

Figure 7 is a vertical transverse sectional view of the hub member and lever, the section being taken on the line 7-7 of Figure 6.

Referring now to the drawings, and to this 80 preferred form of my invention which I have illustrated therein, the numeral 1 generally designates the outer wall of the side of a car of any approved type having suitable window sash indicated at 2 and forming an outer closure for a door pocket or space 3. The inner closure for this space is composed of the lining of the side of the car consisting of a plate 4 and a sash 5 which latter is opposite the sash 2 so as to afford a view from the interior of the car to the outside. This pocket at one end opens into the doorway or space indicated at 3 in Figure 1. In the upper part of the doorway and extended on into the door pocket is a door track 6 secured to a wooden filler 7, itself fastened to one of the upper side beams 8 of the car structure. On this track are mounted door wheels 9 whose spindles 10 pass through or are otherwise connected with the door indicated at 11 and made, preferably of two or more sections hinged or articulated together as indicated at 12, so that in cases where the sides of the car converge or are curved, and the door track is likewise positioned, the door will the more readily conform itself to such contour and be the more easily opened and closed.

95 Secured to one edge of the door, that 100 which faces the doorway 3, is a dash-pot 110

composed of a piston 13 mounted on a rod 13^a connected to the door by a bracket 14 through bolts 15, and of a cylinder 16 also secured to the door by means of a flange 17 and screws or other fastening devices 18 extended through the flange and embedded in the material of the door. This dash-pot has an inlet port, as seen in Figure 2^a, and as indicated at 19, with a ball valve 20 adapted to close the inlet when the piston descends and to open the inlet and recede against a stop pin 21 when the piston is elevated, so that air may be drawn into the dash-pot on the up-stroke of the piston. An exhaust port 22 of small dimension and regulated by screw 23 permits the escape of the air from the dash-pot cylinder when the piston descends, so as to check the piston as it nears the limit of its movement, whereby the momentum of the door, which is made to slide across the doorway, is checked to prevent the door from slamming hard against its jamb.

To the piston 13 is secured an arm 24 to which is attached the operating lever 25. This lever is to be itself actuated through the arc of half a circle from the position shown in full lines in Figure 1 to that shown in dotted lines, so as to draw the door across the doorway, and back again to open the doorway and run the door into its pocket in the side wall of the car.

I will now refer to the electrically operated means which I employ for this purpose. On a base composed of blocks 26 stationed on the car floor 27, I place and secure a bracket 28 as by means of pins or bolts 29. To this bracket I secure as by means of nuts and bolts 30, a housing or casing designated generally 31 and comprised of a shell 32 and a cover 33 which are secured together by nuts and bolts 34 as seen in Figure 3.

On the bracket 28 I also mount a standard 35, suitably secured thereto and adapted for connection with the casing 36 of an electric motor of any approved type capable of having its armature reversed or of rotating first in one direction and then in the other. The armature shaft 37 is connected, as by a coupling sleeve 38 of insulating material, to a worm shaft 39 mounted in a housing 40 which forms, in effect, part of the general casing 31. By referring to Figures 3 and 4 it will be seen that this worm shaft car-

ries a worm 41 which meshes with an annular clutch member 42, being in the nature of a gear having worm teeth 43 which mesh with the worm. This clutch member is rotatably mounted within the casing on ball bearings comprised of ball races 44 and 44^a, the former secured between flanges 45 projected from the gear-like clutch member 42, and shoulders 46 formed on the shell 32 and the shouldered disk 47 secured to the shell by a screw 48; while the race 44^a is secured

between a similar flange 45^a projecting from the cover 33 and a hub 49. Sleeves 50 and 51 are screwed, respectively, on the flange 45 and flange 45^a to further retain the ball races 44 and 44^a in their proper position.

The hub 49 is fitted at 52 to the cover 33 and at 53 against it, so as to turn within the cover and within the inner member of the ball race 44^a when its stud 54 is oscillated or partially rotated by the clutch member 42 through the intermediate devices presently to be described. The hub member carries and therefore swings or oscillates the door lever 25. To this end a bar holder is secured to the flange 55. This holder consists of a plate 56, as seen in Figures 3 and 6 and is attached to the flange 55 of the hub by means of bolts and nuts 57, which bolts pass through one series or the other of the holes 58 and 59 according to the desired relative positioning of the holder on the hub, a consideration determined by the position of the operating lever 25 with the door. This holder is recessed as indicated more clearly at 60 in Figure 6 to permit a partial rotation of the holder before the shoulders 61 thereof come in contact with this actuating bar to swing it from one position to the other as indicated in full and dotted lines in Figure 1. This permits the motor to get a start or in other words enables the armature to acquire a sufficient momentum to cause the holder to swing the bar and overcome the inertia of the door in either of its standing positions—opened or closed position. In order to prevent the shoulder 61 contacting with the bar with a blow, the holder is equipped with yielding buffers comprising slidable bolts 62 mounted in corner projections 63 of the plate 56 and normally projected by coil spring 64. Hence when the holder is put in motion, the buffers 62 on opposite sides of the center first come in contact with the bar and in doing so yield or recede to permit the shoulder 61 to engage the bar softly, the bar having started to swing by the advance contact therewith of the buffers before the shoulders actually reach the bar.

A stud shaft or projection 65 projects from the holder and fits an opening in the bar so as to prevent the bar from longitudinal movement with reference to the holder.

It will now be seen that whenever the hub is given a partial rotation through substantially 180 degrees by the rotation, in one direction or the other, of the clutch member 42, acting through the intermediate devices, the bar will be swung through such 180 degrees and will thereby cause the door to move from open to closed position and vice versa. It is shown in open position in Figure 1, the door in that figure being within the pocket 3 and not in the door opening.

Suitable stops 66 and 66^a project from the

cover 33 and are so positioned that they limit the swing of the oscillatory head by which the hub is operated.

This oscillatory head, of which the hub 49, in effect, forms a part, further consists of an arm 67 mounted fixedly on the stud shaft 54 of the general hub 49. Therefore when the arm 67 is given a movement it carries with it the hub and consequently the bar holder 56 and hence the lever 25 carried thereby and before referred to. The means for causing the clutch member 42 to rotate the arm 67 anti-clockwise so as to withdraw the door from the pocket and close it across the doorway, as the parts are viewed in Figure 1, consists of a detent 69 pivoted to a clip 70 mounted on a stud 71 carried by the arm 67. When the parts are in what may be called normal position, such as shown in Figure 1, and the door is opened, the clutch member 42 will rotate anti-clockwise when the motor is operated. This detent 69 will then occupy the position shown in dotted lines in Figure 4. It will bear against the inner surface of the clutch member, through the contracted action of the spring 72 secured to the detent and fixed at its other end. When one of the recesses 73 of the clutch member reaches the detent the latter will snap into it as shown in full lines in Figure 4. The continued rotation of the clutch member will therefore force the detent, the clip 70 and thence the arm 67 in a rotary direction anti-clockwise and thereby swing the lever from the right to the left, as seen in Figure 1.

When, however, the arm 67 reaches the stop 66^a, as shown in Figure 5, the lever 25 will have made its required movement and the arm 67 will stop, but the clutch member will travel slightly further and withdraw its socket 73 from the detent 69 and leave the detent in the position shown in dotted lines in Figure 4. By that time the clutch member will have itself come to a stop because the circuit will have been broken by the automatically opening and closing electric switch with which the motor circuit is connected, but which switch and circuit wires are not shown because they may be of any conventional type and are no part of this invention.

Thus in the example here given the door will now stand closed or across the doorway. When the operator again starts the motor he will do so by the appropriate switch which will cause it to rotate in the opposite direction from that in which it has just been rotated. The effect of that will be to rotate the clutch member clockwise. In its initial movement the periphery of the clutch member will slide past the detent 69 now in the dotted position shown at 67 but again under the influence of the spring 72 the detent will snap into the first recess 73 which arrives

opposite the detent. This will take place rather suddenly and to prevent breakage of parts or any possible stalling of the motor, the movement thus suddenly applied to the detent 69 is yieldingly applied through the fact that the clip 70 is pivotally mounted on the arm 67. This clip yields or swings slightly on this pivot when this action takes place. The springs, of which there may be one or more, indicated at 74, yield to permit this yielding or tilting of the clip 70. One end of these springs is attached to the clip as at 75 and the other end is similarly attached, as shown at 76 to a bar 77, which in effect is a rigid device, being secured to the arm 67 by a pin 78 and resting against the projection 78^a extending from the arm 67 and constituted of a fitting in a hole in the arm and having a head against which the bar rests. But of course this detail is not material.

This bar 77 also supports one end of the spring 72, before referred to.

It will be seen that the clip 70 has a shoulder 79 which comes against one edge of the arm 67. This shoulder forms a stop against which the springs 74 draw the clip 70 when the parts are in a normal position, and which shoulder moves off from the arm when the clip yields or turns slightly on the pivot 71 as above stated.

It will now be understood that the arm 67 is under motion in a clockwise direction, whereby the hub 49 and the bar holder 56 will be operated to throw the lever 25 from the dotted position, in which the door is closed, to the full line position in which the door is open or back in the pocket, as shown in Figure 1. This clockwise movement of the arm 67 continues until it comes in contact with the stop 66. By that time the door will have been positioned within the pocket.

When the door is again opened and later closed, these same operations are performed. The arm 67 is secured to the hub 49 through bolts 80 which pass through the arm 67 and thence into and through the hub, in the recess 81 of which these bolts terminate where their nuts 82 are applied as seen in Figure 3. As also seen in that figure the arm 67 is turned to one side at its outer end so as to come in the path of the stops 66 and 66^a.

It will now be seen that my invention provides a ready power means of operating car doors from closed to open position, and vice versa. Also that it comprises these several major parts, a casing, a clutch member and means to operate it through a motor; an oscillating head comprising an arm with detent mechanism and yieldable devices to enable the clutch member to actuate the head without breakage or injury of the parts, and that this head includes a sort of hub; a bar holder carried by the hub device and a door operating bar carried by the holder. The construction of each of the major elements

may vary and minor parts may be modified in great variety without departing from the spirit of my invention. Two of the characteristic features, I may add, are the rotatable clutch member adapted to have a rotary reciprocating motion, and the oscillatory head with its bar holder adapted to receive and acquire like motions through and from the clutch member.

10 It will be understood that I desire to comprehend within my invention such modifications as may be necessary to adapt it to varying conditions and uses.

Having thus fully described my invention, 15 what I claim as new and desire to secure by Letters Patent of the United States, is:

1. In a device of the character described, the combination with a door and a reversible motor, of a door operator comprising a rotatable clutch member positioned in essentially a vertical plane and adapted to receive motion in either direction from the motor, an oscillatable head within the clutch member having its axis essentially 20 horizontal and adapted to receive motion first in one direction and then in the other from said rotatable clutch member, and a connection operating in essentially a vertical plane between such head and the door, whereby the door may be power-opened and 25 closed.

2. In a device of the character described, the combination with a sliding door and a reversible electric motor, of a door operator comprising a rotatable clutch member positioned in essentially a vertical plane and adapted to receive rotary motion from the motor, an oscillatable head within the clutch member having its axis essentially horizontal 30 and adapted to receive motion first in one direction and then in the other from said rotatable clutch member, an actuating arm operating in essentially a vertical plane and connected with said head, and a connection 35 between said arm and said door including a dash pot device comprising a cylinder having air inlet and outlet ports, a piston connected to the operating arm and a guide for the piston.

3. In a device of the character described, the combination with a reversible motor, of a door operator comprising a worm screw connected with the motor, a clutch member having worm teeth meshing with the worm, an oscillatable head mounted within the clutch member, mechanism to cause such clutch member to actuate said head, a hub device included in said head, a bar holder 40 connected to the hub device and a door-actuating bar carried by the head.

4. In a device of the character described, the combination with a motor capable of rotating in either direction, of a door operator 45 comprising a casing, a worm shaft mounted thereon and adapted to connect with the

motor, a clutch member in the nature of an annulus having worm teeth to mesh with the worm shaft, an oscillatable head mounted in the casing and within the clutch member and comprising an arm having a detent 70 for engagement by the clutch member, a hub device connected with the arm, a bar holder connected with the hub device and a door actuating arm carried by the holder, the holder being adapted to move through initial movements before operating the arm.

5. A device of the character described, comprising a casing, a clutch member, in the form of an annulus, gearing to rotate said member, an oscillatable head comprising an 80 arm carrying a detent, a hub device connected with the arm, a bar holder connected with the hub device and having a recess widened at its outer extremities and carrying yielding buffers, and a door operating arm pivotally mounted in the holder and adapted when the holder is rotated to be engaged first by the buffers and then by the walls of the recess of the holder.

6. A device of the character described, 90 comprising a mounting structure, a clutch member rotatably mounted in said structure, an oscillatable head also mounted therein and comprising an arm, a detent carried thereby adapted to be engaged and disengaged by the clutch member to actuate and release said arm, a hub device connected with the arm, a bar holder secured to the hub device and including a plate with a transverse recess widened at its outer extremities and having yielding buffers located near such extremities, and a door actuating bar pivoted within the holder plate and located in the recess and adapted to be engaged by the buffers and actuated when the recessed walls contact with it.

7. In a device of the character described, a clutch member in the form of an annulus having recesses, an oscillatable arm mounted within the annulus, stops at substantially diametrical points to limit the oscillation of the arm, a clip pivoted to the arm, a detent mounted on the clip and adapted to enter recesses in the clutch member, and springs 100 acting to normally hold a part of the clip against the arm and to yield to permit the clip to move on its pivot when the detent is first engaged by the clutch member in moving the arm from one position to the other.

8. In a device of the character described, the combination with a clutch member in the form of an annulus having recesses and stops at diametric points, of an oscillatable head comprising an arm, a clip pivoted to the arm, a detent pivoted to the clip and adapted to enter recesses in the clutch member, springs connected to the clip to hold a part of it normally against the arm and to yield during the initial movement of the 115 120 125 130

detent when engaged by the clutch to move the arm from one position to the other, a hub device secured to the arm, a bar holder secured to the hub device and having buffers and a recess widened at its ends, and a door actuating bar pivoted to the head and adapted when the head is rotated to be engaged and moved first by the buffers and then by the walls of the recess.

10 9. In a device of the character described, an oscillatable head mounted in a horizontal bearing and comprising an arm secured near one end of the head, a hub device at one side of the arm and connected therewith, 15 a bar holder at the other side of the hub and connected to the hub device, and a door actuating bar carried by the holder and adapted to be operated in a vertical plane.

10 10. In a device of the character described, 20 the combination with a casing, of an oscillatable head mounted therein and comprising an arm, a hub device secured thereto, a bar holder attached to the hub device and having yielding buffers and a recess widened at 25 its ends, a door actuating bar pivoted to the holder and adapted to be actuated when engaged first by the buffers and then by the walls of said recess.

11. In a device of the character described, 30 the combination with a casing, of an annular clutch member mounted therein, gearing to rotate said member, an oscillatable head mounted in the casing within said member and comprising an arm having a spring actuated detent adapted to be engaged by the 35 clutch member, a hub device connected with said arm, a bar holder adapted to be attached to the hub device and having spring buffers, a recess widened at its ends, and a 40 stud, a door actuating bar pivoted on said stud and loosely fitted within said recess, and stops on the casing to limit the movement of said arm to substantially 180 degrees.

45 12. In a device of the character described, the combination with a casing, a removable cover and diametrical stops within them, of a worm shaft mounted within the casing, a clutch member annulus having worm teeth to engage said shaft and having recesses,

ball bearings to support said annulus, and an oscillatable head mounted in said casing and cover, and ball bearings therefor, such head comprising an arm, a clip pivoted thereto, a detent carried by said clip, springs 55 connected to the clip at one end and a substantially fixed device at the other end adapted to permit the clip to yield when the detent is engaged by the annulus to move the arm in one direction, a hub device secured to the arm, a bar holder comprising a plate adapted to be secured to the hub device and having a recess widened at its ends and provided with a stud, and a door actuating arm pivoted on said stud and located within said recess, all substantially as described.

13. In a device of the character described, the combination with a sliding door and a reversible electric motor, of a door operator comprising a rotatable clutch member positioned in essentially a vertical plane and adapted to move in accordance with the movement of the motor, an oscillatable head within the clutch member having its axis in 70 essentially a horizontal plane, clutch mechanism coacting with the clutch member to actuate said head in accordance with the movement of the clutch member, a hub device included in such head, a bar holder carried by the hub device and a door actuating bar operating in essentially a vertical plane and carried by said holder and connected with the door.

14. In a device of the character described, 85 a door operator comprising a clutch member positioned in essentially a vertical plane, an oscillatable head having its axis in essentially a horizontal plane, mechanism between the head and clutch member whereby the head is actuated in accordance with the movement of the clutch member, a bar holder positioned in essentially a horizontal plane and connected with the head, and a door operating bar carried by the holder and adapted to be actuated thereby in essentially 90 a vertical plane.

In testimony whereof, I affix my signature.

THOMAS ELLIOTT.
